UNITED STATES PATENT OFFICE

JOSEPH T. CONWAY, OF CLEVELAND, OHIO

CLOSURE OPERATOR

Application filed December 26, 1928. Serial No. 328,450.

My invention is an improvement in closure operating mechanism and relates more particularly to means for opening closures such as engine house and garage doors and then 5 automatically closing the same upon the expiration of a predetermined period of time.

One of the objects of my invention is to open and then automatically close doors or other closures at the expiration of a predetermined period of time.

Another object of my invention consists in providing power operated means for opening and closing doors but permitting manual operation thereof without interference from the 15 power operated means.

A further object is to prevent accidental or premature closing of the doors as the result of external forces such as wind.

Another object of my invention is to give 20 ample warning to passersby that the doors are being opened and that a vehicle is about to leave the building.

Another object is to automatically release trap doors such as are used in fire engine 25 houses communicating one floor of the building with another, almost simultaneously with the energization of the motor circuit.

Another object of the invention is to simultaneously sound alarms, release traps and 30 open the doors, when the invention is applied to fire engine stations, the said alarms being de-energized before the doors are automatically closed.

Further objects and advantages of my invention will become more apparent as the 35 following description of an embodiment thereof progresses, reference being made to the accompanying drawings in which like reference characters are employed to designate like parts throughout the same.

Figure 1 is a diagrammatic view of the 40 electrical circuit employed in connection with my invention showing certain of the parts in dotted and full line positions.

Figure 2 is a bottom plan view of one embodiment of my invention shown in use as applied to doors swinging about a vertical axis and showing the extreme positions of some of the parts of the apparatus when the 45 doors are in closed or open position.

Figure 3 is a side elevation of a portion of an apparatus embodied in my invention in which the cover plate of a switch box has been removed.

Figure 4 is an enlarged fragmentary view 55 of a portion of the track showing the carriage in one of its limits of movement along the track.

Figure 5 is an enlarged fragmentary view 60 of another fragmentary section of the track representing the forward end of the track and showing the manner of supporting the means for moving the carriage along the track.

Figure 6 is an enlarged sectional view 65 taken on line 6—6 of Figure 3.

Figure 7 is a sectional view taken on line 7—7 of Figure 5.

Figure 8 is an elevational view of the cylinder movable with the carriage showing the 70 by-pass connection for the cylinder.

Figure 9 is an enlarged section taken on line 9—9 of Figure 3.

Figure 10 is an enlarged section taken on line 10—10 of Figure 3.

Figure 11 is an enlarged elevation of a 75 part of my invention including means for locking the doors in open positions and against accidental closure.

Figure 12 is a section taken on line 12—12 of Figure 11.

In the accompanying drawings illustrating 80 one embodiment of my invention and referring more particularly to Figures 2 to 8 inclusive, 1 represents a frame for doors or other closures 2, which in the present embodiment are mounted to move about a vertical axis.

I have provided means for moving the doors about their respective axes, which in the present embodiment I have illustrated 85 as including connecting rods 3 pivotally connected at one of their ends to the doors, as at 4, and pivotally connected at their other respective ends 5 to the carriage 6. The carriage is movable along a track or other support 7, and in Figure 2 I have illustrated the position of the carriage and connecting rods in full lines, indicating their position when the doors are closed, while in dotted lines I have illustrated these parts in their 90

respective positions when the doors are open.

Referring more particularly to Figures 4, 5, 6 and 7, it will be seen that the track consists of a substantially inverted U-shape channel 8 supported within a casing 9, one end of the track assembly being supported upon the door frame 1 by means of a bracket 10, while the other end is suspended from the ceiling by means of a rod 11. One end of the casing 9 is supported in a housing 12 as shown more clearly in Figure 4. This housing is provided with a rearwardly extending shoulder 13 to which the supporting rod 11 is attached. A depending stop or abutment 14 is also formed on the housing and is disposed in the path of movement of the carriage for purposes which will be described more fully hereinafter. The forward end of the casing 9 is supported within a housing or casting 15 which terminates in a bracket 10, by means of which it is supported on the door frame 1.

The carriage 6 consists preferably of a casting having connecting rod supports 16 on opposite sides thereof, by means of which the ends of the rods may be pivotally connected through the bolts 17. A cylinder 18 is preferably formed integrally in the carriage body and its longitudinal axis extends substantially parallel to that of the track, although the cylinder may be separately formed and conveniently secured in position in the carriage body if desired. The carriage is suspended from the track by the rollers 19, which are freely rotatable about shafts which extend through the portion 20 of the carriage body. In the particular embodiment illustrated herein, I prefer to employ rollers having rubber tires, in order to minimize noise in operation such as would be manifested where there is metal to metal contact between rollers and the tracks. It will be noted that the rollers travel along the flat portions 21 of the spaced tracks formed in the channel 8.

A piston 22 provided with suitable packing is mounted to reciprocate within the cylinder 18 and is secured by means of a set screw 23 to the rod 24 which is slidable through openings in the ends of the cylinder 18. I have provided bonnets 25 which are detachably screwed upon each end of the cylinder for slidably supporting the rod 24 therein. These bonnets may also be provided with packing means as at 26. Referring more particularly now to Figure 8, it will be seen that I have provided a by-pass consisting of a restricted conduit 27 communicating with the interior of the cylinder 18 adjacent each end thereof. I have provided a control valve 28 in the conduit for regulating the flow of oil or other fluid through the conduit from one end of the cylinder to the other, when the piston 22 is shifted from one end of the cylinder to

the other. In this manner the carriage may be brought to rest against the desired cushion at either of its extreme positions along the track after the motor has been de-energized by the automatic opening of the respective reversing switches. 70

I have also provided means for moving the carriage 6 from either one of its extreme positions to the other, which includes a belt or chain 30 having its respective ends secured to the turn buckles 31 and 32, which are in turn secured to the portion 20 of the carriage. These turn buckles permit the taking up of slack in the belt or chain from time to time. This is clearly shown in Figure 4. The chain 80 passes over idler sprockets 33 and 34, which are rotatably mounted at the forward and rearward ends respectively of the track 8; the lower portion of the chain extends through the channel 8 while the upper portion of the chain passes over the sprocket 33, the driving sprocket 35 and under the idler sprocket 36 and over the intermediate idler sprocket 37 and about the rear idler sprocket 34. The upper portion of the chain passes 85 through the casing 9. The driving sprocket 35 is keyed to a shaft 38 to which also is keyed a reducing gear 39. The motor M is supported on the casting 15 as shown in Figure 3, and carries on its shaft 40 a gear 41 which meshes with the reducing gear 39. The shaft 40 of the motor extends into a casing 42 which is formed integral with the casting 15, which houses the gears 39 and 41 and the forward end of the track. A conduit 43 200 leads from the motor to the interior of the switch box 44, which is formed as a part of the casting 15 and carries therein electrical conductors 108, 110, 112, 113, between the posts of the motor and certain of the electrical apparatus housed within the switch box. 205

I have also provided means for operating the reversing switches RS and RS¹, which consist of the links 131 and 132 pivotally connected to the respective reversing switches at their outer ends and also pivotally connected to the rod 130. The rod 130 extends substantially parallel along one side of the track and casing 9, and is provided with adjustable lugs or stops 44 and 45 which may be adjusted to the desired positions along the rod 130. The rod 130 is movable axially in suitable bearings to engage one of the reversing switches with its respective contacts 110 and to disengage the other reversing switch from its respective contacts and rod 46 is supported along the track and extends substantially parallel to the rod 130. The rod 46 carries thereon adjustable depending arms 115 47 and 48 which are capable of swinging about horizontal axes 49. These arms may be adjusted by means of set screws, to swing from the rod 46 at any desired point thereon, which may be selected by the operator. In 130

the position of the parts shown in Figure 3 with the carriage to the extreme right, it will be noted that the arm 48 is engaged by the carriage in its movement to the right and in turn engages the stop 45 secured to rod 130.

5 In this manner continued movement of the carriage will move the rod 130 to its limit of movement to the right, closing the reversing switch RS and opening the reversing switch RS¹. When the carriage travels towards the left along the track it will engage the depending arm 47 which in turn engages the stop 44 secured to the rod 130. Continued movement of the carriage to the left will cause the rod 130 to be moved to the left, closing the reversing switch RS¹ and opening the reversing switch RS.

The intermediate sprocket 37 is rotatably supported at a point substantially midway between the sprockets 33 and 34 and serves to support the chain 30 at this point during its travel between the sprocket 36 and the sprocket 34. The sprocket 37 is mounted in a casting 50 which is provided with shoulders 51 for supporting the ends of the casing section 9. This is shown in detail in Figure 5. The cross-brace 52 is also provided in the casting 50 and is rigidly secured to a wall of the channel 8 by means of rivets or other 30 fasteners 53. It will be noted that the heads of the fasteners 53 extend but a short distance into the channel 8 to provide clearance for a portion of the carriage as it passes therethrough.

25 In Fig. 1 I have illustrated diagrammatically some of the electrically controlled apparatus employed in operating one or more closures, and I have also illustrated in this figure the electrical circuits used in connection with this apparatus. I will now proceed to describe these circuits. L¹ and L² indicate a source of electrical energy and F indicates protecting fuses in each side of the line. For convenience of description L² may be designated as the side of the line common to all the electrically connected devices. L¹ is connected through a conductor L¹ and snap switch A to the manually operated switches B and C. The switches B and C are of the 40 normally open or push button type, since it is only necessary to close one of the switches momentarily to energize one of the respective solenoids S and S¹. When the switch B is depressed, current will flow from L¹ through the normally closed switch A, the switch B and conductor 100 through the solenoid S and conductor L², part of the current passing along the conductor 101, the solenoid S² and the conductors 103 and L². The solenoid S² 45 actuates the plunger P, when energized, to lift the latch L⁵ on the doors 2 through the lever L⁴ and rod R³. The solenoids S and S² are energized simultaneously.

Also when the switch B is closed current 50 will flow along the conductor 104, the sole-

noid S³, the conductors 105 and L², energizing the solenoid S³. The plunger P¹ of the solenoid S³ is connected to actuate a trip or latch L³ for releasing the trap doors T¹ and T². An audible alarm A¹ and a light A² are connected across the lines 104 and 105.

When the doors 2 are closed the reversing switches RS and RS¹ and the plunger P² and automatic switch blades are in the dotted line positions indicated in Fig. 1, before the push button switch B is closed. Upon closing the switch B momentarily electric current will energize the solenoid S drawing the plunger P² to the right in the figure, engaging the automatic switch blades B¹, B², B³ and B⁴ with the respective contacts C¹, C², C³ and C⁴ and disengaging the blades B⁵, B⁶, B⁷ and B⁸ from the respective contacts C⁵, C⁶, C⁷ and C⁸ of the switch. In this manner a motor circuit is established as follows:

25 Part of the current passing through the switch A passes along the wires 106 and 107 to the blades B¹ and B² which are now in contact with the contacts C¹ and C² of the automatic switch. From the contact C¹ a wire 108 carries the current from L¹ to post M² of the motor M, and from the contact C² a wire 109 also carries the current from L¹ and wire 107 to the blade B⁹ of the reversing switch RS. A wire 110 leads from the contact engaged by B⁹ to post M⁴ of the motor. L¹ is therefore connected to posts M² and M⁴ of the motor during this phase of the operation of the apparatus.

30 A wire 111 leads from the contact C⁴ and blade B⁴, which is connected to L², to blade B¹⁰ of the reversing switch RS. A connection is thus made from L² through the blade B¹⁰ and a wire 112 to post M³ of the motor M. Another connection is made from L² through the blade B³, contact C³ and wire 113 to post M¹ of the motor. L² is therefore connected to posts M¹ and M³ of the motor M during this phase of the operation of the apparatus.

35 It will also be noted that the siren A³ and street light A⁴ will be energized immediately upon the engagement of the blade B⁴ with the contact C⁴ which completes the alarm circuit and warns passersby that the doors are being opened. The alarm circuit just referred to may be traced as follows—Current passing from L¹ through the switch A and wire 106 will continue through the wire 114 and the normally closed contacts C⁹ and C¹⁰ of the switch D, to the siren A³ and light A⁴ through the wire 115. A wire 116 connects through the contact C⁴ and blade B⁴ to L² completing the alarm circuit. The devices A³ and A⁴ will continue to be energized as long as the doors 2 remain open and the blade B⁴ engages contact C⁴, and as long as the switch arm D engages the contact C¹⁰.

40 I have provided means for automatically energizing the solenoid S¹ after a predetermined period of time has elapsed since the

energization of the solenoid S^1 and I have also provided manually controlled means for energizing the solenoid S^1 at will, the latter constituting more of an auxiliary means to be used when it is desired to close the doors before the solenoid S^1 is energized automatically. I will trace first the circuits employed for automatically energizing the solenoid S^1 . Part of the current from L^1 passing through the normally closed switch A and wire 106 passes along the conductors 114 and 117 through coil R , which is of relatively low resistance and thence through coil R^1 which is of relatively high resistance.

The two coils are connected in series by the wire 118, the wire 119 leading from the coil R^1 and connecting to L^2 through the wires 119 and 111 and blade B^4 of the automatic switch. The coil R^1 extends axially within a thermally responsive element T . This element consists preferably of a spirally wound metallic strip anchored at its lower end 120 in a suitable support and carrying an outwardly extending arm 121 at its upper end. The arm 121 terminates in an insulated head 122 which normally abuts an adjusting screw 123 in the circuit maker and breaker D . Thus it will be seen that as the coil R^1 heats up, the spiral thermostatic element T will respond to the rise in temperature by expanding spirally, whereupon the arm 121 carried by the element and abutting the adjusting screw 123 carried by the switch arm D will move the hinged switch arm toward the observer (Fig. 1) breaking the contacts through C^{10} which is behind the arm 121 and the switch arm D . As the switch arm continues to move toward the observer by continued spiral expansion of the thermostat T it will contact with the contact C^{11} feeding current from L^1 through the wires 106 and 114 and switch arm D and wire 124 to the solenoid S^1 . The solenoid S^1 is connected to the wire L^2 through the wire 128 to complete the circuit. It will be seen that the movement of the switch arm, which is normally held against the contact C^{10} by a spring 126 toward the contact C^{11} , first breaks the circuit through the siren A^3 and lamp A^4 and then completes the circuit through the contact C^{11} to energize the solenoid S^1 and pull the plunger P^2 to the left in the figure. When the plunger moves to the left the blades B^1 , B^2 , B^3 and B^4 are disengaged simultaneously from the respective contacts C^1 , C^2 , C^3 and C^4 of the automatic switch, while the blades B^5 , B^6 , B^7 and B^8 are engaged with the respective contacts C^5 , C^6 , C^7 and C^8 .

As the doors approach the limit of movement representing their open position, the rod 130 is moved to the left in Figure 1 by means which have been described hereinbefore. One end of this rod is connected by links 131 and 132 to the reversing switches

RS and RS^1 respectively, and movement of the rod to the left will engage the blades B^{11} and B^{12} with the contacts C^{12} and C^{13} , and C^{14} respectively and will disengage the blades B^9 and B^{10} from the contacts C^{15} and C^{16} respectively. I have represented these positions of the reversing switches, rod and links by dotted lines in the figure.

It will be noted that when the solenoid S^1 is energized by the closing of the circuit through the switch D and contact C^{11} , the blades of the automatic switch are moved to the positions shown by dotted lines and the heater circuit through wires 119, 111 and contact C^4 is broken. However the return of the switch arm D to its normal position to close the contacts D and C^{10} is retarded by the cooling of the coil R^1 and the contraction of the thermostat T . In this manner the automatic circuit through the solenoid S^1 is of short duration. With the switch blades B^5 , B^6 , B^7 and B^8 in contact with the respective contacts C^5 , C^6 , C^7 and C^8 and the reversing switches RS and RS^1 in the dotted line position, a motor circuit is established for rotating the motor armature in a reverse direction to that when the doors are being opened. This circuit may be traced as follows—Current from L^1 flows through the wire 106, blade B^6 , and wire 108 to post M^2 of the motor. Current also flows from L^1 and wires 106 and 107 through blade B^6 , wires 133 and 113 to post M^1 of the motor. Post M^3 of the motor is connected to side L^2 of the power line through wire 112, blade B^{12} , wire 134, contact C^7 , and blade B^7 , while post M^4 of the motor is also connected to L^2 by means of the wire 110, blade B^{11} of the reversing switch, wire 135 and blade B^8 of the automatic switch.

It will be noted then that the posts M^1 and M^2 are connected to L^1 and that posts M^3 and M^4 are connected to L^2 to operate the motor in one direction for closing the doors, while with automatic switch in the position shown in full lines, posts M^1 and M^3 are connected to L^2 and posts M^2 and M^4 are connected to L^1 . With the automatic switch in the dotted line position the motor is actuated to close the doors by means which have been described. As the doors approach the closed position the rod 130 is shifted to the right in Figure 1, whereupon the reversing switches RS and RS^1 will again assume the full line position and the motor circuit will be automatically broken.

When the reversing switches RS and RS^1 are in the dotted line position a circuit is completed to operate a latch or lock L which holds the doors in open position and against accidental or premature closure by wind or other forces. This circuit remains closed only to unlock the latch while the automatic and reversing switches are in the dotted line position and while the motor is operating the

means for closing the doors. This latch circuit may be traced as follows—Current from L^1 passes along the conductors 106 and 136 through the solenoid S^4 and wire 137 to the contact C^{12} . The switch RS^1 being in closed position, the current passes along the wire 135 and blade B^8 to L^2 . A plunger P^4 arranged to operate the latch operates within the solenoid S^4 when the latter is energized.

I have shown the means for operating the latch L in Figures 11 and 12, which includes a bell crank 60 operable by the plunger P^4 to lift the latch L through the connecting link 61. The hooked end of the latch engages one or more stops 62 on one of the connecting rods 3. When the doors are opened the rod 3 moves to the left in Figures 11 and 12, the hooked end of the latch riding up the inclined walls 63 and over the stops 62 providing a positive lock to retain the doors in open position. When the doors are to be closed, however, and the solenoid S^4 is energized, the latch will be lifted out of the path of movement of the rod 3 to the right.

I have provided a manually controlled electrical circuit for energizing the solenoid S^1 when it is desired to close the doors before the thermostat T has had time to move the switch D into contact with the contact C^{11} . This circuit includes a push button switch C connected on one side to L^1 and on the other side by means of a wire 138 to the solenoid S^1 . A conductor 128 connects the other lead of the solenoid to L^2 of the line.

The switch A may be opened any time to disconnect the power line. Thus the doors may be maintained in either an open or closed position at will.

I will now describe the operation of my invention as illustrated in the accompanying drawings.

Assuming that the doors 2 are closed and that the various parts of my invention are in the full line position of Fig. 2, in order to open the doors, the operator depresses the push button switch B of Fig. 1 to the full line position, energizing the solenoids S , S^2 and S^3 . The plunger P is thus actuated to release a latch L^4 which normally retains the doors in closed position. This latch is illustrated in Fig. 1.

The plunger P^1 is likewise actuated upon the energization of the solenoid S^3 to release a latch L^3 which has previously been positioned to retain the spring actuated trap doors T^1 and T^2 in closed position as illustrated in Fig. 1. When this latch is released by the solenoid and plunger the trap doors will swing about their pivots to open position. Their movement may be retarded slightly by means of dash pots DP of conventional design. Simultaneous with the energization of the solenoid S^3 , audible and visible signals A^1 and A^2 are energized to indicate the doors are open and to illuminate

the area around the trap doors to prevent accidents.

When the solenoid S is energized, the plunger P^2 is shifted to the right as shown in Figs. 1 and 10, closing the switch blades B^1 , B^2 , B^3 and B^4 with their respective contacts C^1 , C^2 , C^3 and C^4 . In this manner the motor M is energized to run in a direction for rotating the reduction gear 39 and pinion 35 (Fig. 5) in a clock-wise direction. The upper portion of the chain 30 is thus moved to the right in Figs. 4 and 5, while the lower portion moves toward the left, drawing the carriage along the track, and opening the doors 2. In Fig. 2 I have illustrated the carriage in dotted lines in its limit of movement to the left to open the doors.

Referring now more particularly to Fig. 3 it will be seen that, as the carriage approaches its limit of movement to the left in opening the doors, a portion 16 of the carriage body will engage the depending arm 47 which is freely movable about its pivot. Continued movement of the carriage to the left will cause this arm to engage the stop 44 secured to the slide bar or rod 130 and move the stop and rod to the left a sufficient distance to disengage the reversing switch RS from its contacts C^{15} and C^{16} and to engage the reversing switch RS with its contacts C^{12} , C^{13} and C^{14} before the carriage comes to rest. Referring to Fig. 1 it will be seen that opening of the switch RS will disrupt the motor circuit and stop the motor, thus stopping the movement of the carriage substantially instantaneously with the opening of the switch RS .

It should also be noted that when the plunger P^2 is shifted to the right, an alarm and light circuit is closed through the wires 106 and 114, switch contact C^9 and D^7 , contact C^{10} and wire 115 to the streetlight A^4 and the siren A^3 , the circuit being completed through the wire 116, contact C^4 , a switch blade B^4 and wire L^2 . Thus an audible street alarm is given during the opening of the doors 2 to warn passersby that the doors are opening or are opened and a vehicle is about to pass therebetween. The audible alarm and light A^4 will continue to function as long as the switch arm D remains in contact with the contact C^{10} .

A circuit is also established through the regulator and heater coils R and R^1 when the plunger P^2 is in the position shown in Fig. 1. This circuit is traced as follows—from L^1 and switch A , wires 106, 114 and 117 through the coil R of relatively low resistance, wire 118 and coil R^1 of relatively high resistance, wires 119 and 111, and switch blade B^4 to L^2 . Therefore when the blade B^4 engages its contact C^4 current will pass through the relatively low resistance, wire 118 and coil R^1 of relatively high resistance, wires 110 and 111, and switch blade B^4 to L^2 . Therefore, when the blade B^4 engages its contact C^4 current 125

will pass through the relatively low resistance current regulating coil R. The current that passes through this coil is conducted through the wire to the heater coil R¹, of relatively high resistance. The coil R¹ is mounted within a thermostatic element T, which is responsive to a rise in temperature of the coil R¹. When the coil R¹ is energized the material of the thermostatic element T will expand and cause the convolutions thereof to unwind slightly to move the insulated arm 121 secured to one of its ends, to move toward the observer in Fig. 1. The set screw 123 may be adjusted toward or away from the disc 122 to determine the time interval between the energization of the coil R¹ and the closing of the contacts D and C¹¹ and also between the energization of the coil and the breaking of the contact C¹⁰ of the alarm circuit. Thus if it is desired that the de-energization of the alarm and the closing of the contacts D and C¹¹ be retarded, the set screw 123 may be adjusted away from the disc 122 when the coil R¹ is cold, although it is obvious that by adjusting the set screw closer to the disc 122 the elapsed time between the energization of the coil R¹ and the beginning of movement of the switch D about its axis will be correspondingly shortened. By this means the energization of the solenoid S¹ and the de-energization of the street alarm A³ and light A⁴ may be predetermined over desirable periods such as, for example, from fifteen seconds to two or three minutes after the coil R¹ is energized. A compression spring 126 normally returns the switch arm D into contact with the alarm contact C¹⁰ and breaks the contact C¹¹, as it overcomes the subsiding expansive forces of the cooling element T when the same is de-energized.

From the foregoing it will be seen that when the switch arm D contacts with the contact C¹¹ a circuit is completed through the wires L¹, 106, 114 and 124 to the solenoid S¹, the other side of the solenoid being connected to L² through wire 128. In this manner the plunger P² is moved to the left in Fig. 1, disengaging the blades B¹, B², B³ and B⁴ from their respective contacts and engaging blades B⁵, B⁶, B⁷ and B⁸ with the respective contacts C⁵, C⁶, C⁷ and C⁸. With the control switch blades in this position as shown in Fig. 1 in dotted lines, a motor circuit is established to rotate the motor armature in a reverse direction to that when the doors 2 were being opened. This motor circuit may be traced from L¹, wires 106 and 107 to blades B⁵ and B⁶. From contact C⁵ one side of the motor circuit extends through wire 108 to post M² of the motor M. From contact C⁶ current is carried by means of conductors 133 and 113 to post M¹ of the motor M. L² of the current supply is fed to contacts C⁷ and C⁸ through the blades B⁷ and B⁸ and the wires 134 and 135 to the re-

versing switch RS¹. When this switch is closed by the movement of the rod 130 to the left Fig. 1 in opening the doors 2, the motor circuit is completed through wires 111 and 112 to posts M⁴ and M³ respectively of the motor. Part of the current from L² passes through the conductor 137 when the reversing switch RS¹ is closed to engage contact C¹², energizing the solenoid S⁴ which is also connected to L¹ through the wires 136 and 106. Energization of the solenoid S⁴ retracts the plunger P⁴ which in turn releases the latch shown in Figs. 11 and 12. This latch, as has been described above, normally serves to hold the doors against accidental closing which might result from wind or other external forces.

When it is desired to energize the solenoid S¹ prematurely, that is, before the same is actuated by the automatic means described above, the operator depresses the push button switch C which will close the circuit from L¹ through wire 138 and the solenoid S¹ to L². Thus the doors may be closed at will without waiting for the automatic switch D to function.

It will be observed that when the doors 2 are closed the contacts C¹⁷ on one of the doors engage the contacts C¹⁸ on the door frame to close the circuit through the solenoid S². Thus the circuit through this solenoid is broken when the doors 2 begin to open. In Fig. 1 I have illustrated these contacts diagrammatically in spaced relation while in Fig. 2 the latch assembly is indicated generally at 200.

My invention may be operated automatically or manually as desired. The automatic operation of the apparatus may be controlled to respond at a predetermined period of time selected by the operator for determining the lapse of time between the beginning of the door opening and closing phases, by simply adjusting the set screw 123 on the switch arm D. The period of time during which the signals A³ and A⁴ are energized is also controlled by this set screw.

By the use of my invention as applied, for instance, to fire engine stations where it is essential that the fire apparatus leave the building as quickly as possible upon the sounding of a box alarm, the doors are in the open position before the fire apparatus is ready to leave, since it is only necessary for the desk man to depress the switch B as he gets the first round of the alarm. In this manner the doors may often be opened before the first round is actually completed. My invention provides for automatic closing of the doors after a predetermined lapsed period of time, which may be from 15 seconds to 2 or 3 minutes without further attention by the desk man, provided the switch A is left in closed position. If it is desired that the doors remain open until 180

the apparatus returns from its run, the desk man opens the switch A, but upon again closing this switch the doors will be closed promptly.

5 If desired, a manually operated switch (not shown) may be inserted in the circuit feeding the signal devices A³ and A⁴, to prevent their energization when the doors are opened for purposes other than to admit or

10 to discharge the fire apparatus.

It will be noted that if the source of electrical energy at L¹ and L² should fail for any reason while the doors are in open position, the doors will not begin to close imme-

15 diately upon the restoration of the current source, but the closing will be retarded until the coils R and R¹ heat and the thermostatic element T operates the switch arm D to close the circuit through the solenoid S.

20 If the current source should fail when the doors are closed and an alarm comes in, the doors may be manually opened without interference from the door opening mechanism.

25 Various changes may be made in the details of construction and arrangement of parts without departing from the spirit of the invention or the scope of the subjoined claims.

I claim:

30 1. The combination with a closure and a frame therefor, of means for opening and closing the closure, said means including a driving motor, a track extending rearwardly of the frame, a carriage movable on the

35 track, a chain having its ends secured to the carriage and in driving connection with the motor, rods connecting the closure with the carriage, a fluid pressure cylinder movable with the carriage, a slide rod extending

40 through the cylinder and beyond the ends thereof, a piston carried by the rod and operating in the cylinder for cushioning the carriage as it is brought to rest at either of its extreme limits of movement on the track,

45 and stops arranged in the path of movement of the rod to engage the ends thereof as the carriage approaches either of its limits of movement along the track.

2. In an electrically controlled door operating mechanism; a track; a carriage capable of travel along the track; a cushioning device movable with the carriage and including a cylinder, a piston in the cylinder,

55 a rod slidable in the cylinder and fixed to said piston, the ends of the rod extending beyond the ends of the cylinder; stops supported along the track and extending into the path of movement of the cylinder and rod for engagement by the rod as the carriage approaches either of its extreme limits of travel on the track; rods connecting the carriage with a closure for operating the

60 same as the carriage travels along the track; an electric motor, an electrical circuit connecting the motor with a source of electrical

energy; a motor reversing switch in said circuit; a rod extending along the path of travel of the carriage having one end operatively connected to said reversing switch; stops on said last named rod and in the path of movement of the carriage whereby said last named rod may be operated to reverse the switch when the carriage approaches either of its limits of movement.

In testimony whereof I hereunto affix my signature this 3rd day of December, 1928.

JOSEPH T. CONWAY.
